REFRIGERATOR

Harry L. Merrill, Nashua, N. H., assignor to Harder
Refrigerator Corporation, Cobleskill, N. Y., a
corporation of New York

Application July 18, 1938, Serial No. 219,689

5 Claims. (Cl. 62—31)

My invention relates to improvements in refrigerators and particularly to improvements in refrigerators of the general type disclosed in my Letters Patent Nos. 2,062,139, 2,062,140, 2,117,564, and 2,121,640.

5 Water, either in liquid or solid form, is a comparatively poor conductor of heat. It is probably for this reason that warm air flowing directly in contact with the surface of a refrigerant, such as ice, does not lose its heat or become cool as rapidly as it does when flowing in contact with one side of a comparatively thin heat conductor, the other side of which is maintained in direct contact with the surface of the ice. Where this heat transfer takes place through thin metal, and particularly metal having a high coefficient of heat conductivity, the rate of heat transfer is several times faster than the rate directly from air to ice.

10 While the refrigerators disclosed in the above mentioned patents are highly efficient, even when the ice has melted to such a degree as to permit that part of the warm air streams which otherwise would flow against the ends of the ice in 15 the grid valleys to flow through the open ends of the valleys into the refrigerant compartment, I find that this efficiency can be appreciably increased, particularly with a small volume of ice in the refrigerant compartment, by designing the 20 refrigerator in the manner hereinafter described and illustrated in the accompanying drawings in which—

25 Fig. 1 is a fragmentary front elevation view, partially in section, of my refrigerator;

30 Fig. 2 is a fragmentary plan view, partially in section and with parts broken away, of the grid or ice support;

35 Fig. 3 is a fragmentary section of Fig. 2 in the plane 3—3;

40 Fig. 4 is a fragmentary section of the refrigerator in the plane 4—4 of Fig. 1;

45 Fig. 5 is a fragmentary section of Fig. 1 in the plane 5—5;

50 Fig. 6 is a perspective view of the central grid element and one of the side elements in slightly spaced relation;

55 Fig. 7 is an enlarged fragmentary sectional view of one of the side grid elements; and

Fig. 8 is a front elevation view of the refrigerator.

Referring to the drawings, 1 represents the refrigerator cabinet having inner and outer walls 2 and 3, respectively, preferably formed of metal, with insulating material 4 therebetween. The cabinet is provided with a partition 5 which sub-

divides the interior thereof into an ice compartment 6 above and a storage compartment 7 below, and which comprises two layers of sheet metal 8 and 9 having insulating material 10 between them. The partition 5 is secured to the 5 interior front and back of the cabinet in any suitable way such as by welding 11, or by supporting it upon an angle 12. The partition is spaced from the sides of the refrigerator, as shown in Fig. 3, to provide passages 13 and 14 for the upflow 10 of warm air, and is also provided with a central opening 15 for the downflow of warm air. The sheet metal on the top and bottom of the partition is upturned around edges of the central opening, as shown at 16, to form a curb for intercepting 15 water flowing downwardly on the partition toward the central opening and preventing it from dropping into the storage compartment. It is to be understood that the partition 5 is sloped slightly downwardly from the front to the back 20 of the refrigerator to convey water to the usual drain pipe 17, and it will also be noted that the partition slopes downwardly from each side toward the central opening, as shown in Fig. 3, to facilitate the circulation of air in the cabinet. 25 That is to say, warm air, rising in the storage compartment to the bottom of the partition 5, is deflected toward each of the side passages 13 and 14 and the cool air, like water, flows downwardly over the upper surface of the partition toward 30 and into the central opening 15. The grid or ice support preferably comprises three separate pieces, a central element 18 and similar side elements 19, all of which are preferably but not necessarily made of sheet aluminum because of 35 its high heat conductivity and its practical immunity from the corrosive effects of water.

The side elements 19 are formed with a plurality of V-shaped ridges and valleys therein for the purpose of increasing the area of cold metal 40 with which the air to be cooled flows in contact as will be later pointed out. Very satisfactory results have been obtained by making the valleys about 1½" in depth with the ridges about 2½" apart which provides a grid element having more 45 than one and one-half times the surface area of its projection on a horizontal plane. At the ends of the valleys, the metal forming the adjacent sides thereof is bent inwardly as shown at 20 to form closures for the ends of the valleys. By 50 closing the valleys adjacent the warm air passages 13 and 14, the warm air is prevented from directly contacting the ends of the ice which rests upon the grid; it being understood that the ridges, due to their comparatively sharp crests, penetrate 55

trate rapidly into the bottom of the ice and that the ice between the ridges settles down into and substantially fills the valleys. By substantially closing the valleys at the ends adjacent the central cold air opening in the partition, the construction of the central element 18 is greatly simplified. Heretofore, the central element has been formed with depending portions at the sides having spaced openings therein for the passage 5 of air but with solid metal portions in registration with and which serve to block the ends of the valleys. It has been found that, unless the valleys are substantially blocked at the ends adjacent the cold air opening 15, the ice melts into 10 formations, such as icicles, which project over the opening 15 and water drops therefrom into the storage compartment. The side elements 19 are supported on and in spaced relation to the partition 5 by means of the metal straps 21 which are 15 secured thereto. Preferably, the supporting straps 21 which are adjacent the cold air opening in the partition 5 form legs which maintain the adjacent ends of the elements 19 at a somewhat higher elevation than the ends thereof adjacent 20 the warm air passages 13 and 14, as shown in Fig. 3.

In the present type of refrigerator the central element 18 is simply a V-shaped trough of sheet metal, as shown in Figs. 3 and 6. Spaced straps 22 riveted or otherwise secured to the element 18 are provided with hook-like extremities 23 which engage the closures 20 in the valley ends, as shown in Figs. 2 and 3, and the central element 18 is thus supported on or suspended from the ends 35 of the side elements 19 in freely raisable or removable relation thereto. Moisture condenses on the bottom of the V-shaped central element 18 and runs down the sides thereof. For the purpose of intercepting this moisture and preventing the 40 water dropping into the storage compartment, a V-shaped gutter 25 is riveted or otherwise secured to the bottom of the V-shaped element and in slightly spaced relation thereto. This gutter slopes downwardly toward the back of the refrigerator and the water accumulating therein is 45 discharged at the end 30 over the opening 31 in the partition which communicates with the drain 17. Openings 26 are also provided in the bottoms of the valleys in the elements 19 to permit water from the melting ice to drain directly there- 50 through on to the top of the partition 5. Preferably, but not necessarily, runners 27 are riveted or otherwise secured to the side elements 19 to provide skids along which an ice cake 28 may be slid in icing the refrigerator.

Secured to the interior sides of the cabinet, as shown in Fig. 3, are inwardly and downwardly inclined projecting lips 24 which extend to and slightly overlie the ends of the elements 19 and thus serve to cut off the upflow of warm air through the passages 13 and 14 and deflect it into the air ducts formed between the elements 19 and the partition 5, as shown by the arrows in Fig. 3.

65. In operation, when the box is first iced, the ice is supported initially on the runners 27. Due to the concentration of heat and weight on these small area supports, melting here take place very rapidly. The runners penetrate the bottom of the ice and the ice melts down into and substantially fills the valleys in the grid, as shown at 29 in Fig. 5. Warm air rises from the food compartment in two separate streams, one at each side of the interior of the cabinet. These air streams flow through the passages 13 and 14.

70.

75.

and are then deflected toward each other through the air ducts formed between the elements 19 and the partition 5 and toward the central cold air downflow passage 15. In addition to filling the valleys in the side elements 19, the ice also substantially fills the central V-shaped element 18 so that all of the metal of the grid which forms the top of the air ducts is maintained in close contact with the bottom of the ice. The warm air flowing in contact with this comparatively large area of cold, high-heat-conducting metal is rapidly chilled whereby its density is increased so that it flows downwardly into the storage compartment through the central opening 15 in the partition. The downwardly inclined sides of the central element 18 are maintained substantially at ice temperature and therefore also serve to cool the air in addition to deflecting the air streams emerging from the ducts at either side thereof downwardly into a common zone of confluence in and about the cold air downflow passage 15.

By closing the ends of the valleys adjacent the sides of the refrigerator, warm air rising through the passages 13 and 14 and deflected beneath the grid elements 19 is prevented from contacting the ends of the ice in the valleys. The effect of this arrangement is to eliminate undercutting of the ice cake and practically to confine the ice meltage to the bottom of the cake so that the 30 ice, when melted down into a thin layer, extends substantially across the entire width of the grid instead of extending only a comparatively short distance either side of the central element as is the case where the valleys in the elements 19 are 35 open at the ends.

Under normal operating conditions the air to be cooled does not enter the refrigeration chamber but transfers its heat to the ice through the thin metal of the grid which, as pointed out above, provides a more rapid and efficient transfer than is the case where the air is projected directly against the ice. Moreover, since the entire top surface of the grid is maintained substantially at all times in contact with the ice and therefore at ice temperature, this feature also improves the efficiency of the refrigerator. 40 45

While I have described my invention in its preferred embodiment, it is to be understood that the words which I have used are words of description rather than of limitation. Hence, changes within the purview of the appended claims may be made without departing from the true scope and spirit of my invention in its broader aspects. 55

What I claim is:

1. An ice refrigerator comprising a cabinet having a transverse partition therein subdividing the interior of said cabinet into an ice compartment above and a storage compartment below; said partition being spaced from the opposite sides of said cabinet to provide openings for the upflow of warm air, and having a central opening therein for the downflow of cold air; and an ice rack comprising two side elements each formed of a thin metal sheet bent to form a plurality of alternating ridges and valleys in said elements and having portions of said sheet at the ends of said valleys bent across said valleys to form closures therefor, means for supporting said side elements in spaced, freely removable relation to said partition to form passages for the flow of air therebetween from said warm air openings to said central opening, a central element formed of thin sheet metal ex- 60 65 70 75

tending between and spacing said side elements at the top thereof, and means for supporting said central element in freely removable relation to said side elements and to said partition.

5. 2. In a refrigerator of the character described, an ice support comprising two side elements formed of thin sheet metal having a plurality of alternating ridges and valleys therein; portions of said metal being bent across said valleys 10 at the ends thereof to form closures therefor; and a central element of thin metal disposed between said side elements, and supported upon the closures for said valleys.

3. In a refrigerator of the character described, 15 an ice support comprising two side elements formed of thin sheet metal having a plurality of alternating ridges and valleys therein; portions of said metal being bent across said valleys at the ends thereof to form closures therefor; a 20 central element of thin sheet metal formed with a comparatively deep trough therein, and means cooperating with the central element and the closures for said valleys for supporting the central element between the side elements.

25. 4. In a refrigerator of the character described, an ice support comprising two similar side elements formed with a plurality of alternating ridges and valleys therein, and a central element supported on said side elements and freely lift-

able therefrom, whereby it may be readily removed to facilitate cleaning; said central element being provided with a valley therein angularly disposed to the valleys in said side elements.

5. An ice refrigerator comprising a cabinet 5 having a transverse partition therein subdividing the interior of said cabinet into an ice compartment above and a storage compartment below; said partition being spaced from the opposite sides of said cabinet to provide openings 10 for the upflow of warm air, and having a central opening therein for the downflow of cold air; and an ice rack comprising two side elements formed of thin metal with a plurality of V-shaped valleys therein which are closed at each 15 end, means for supporting said side elements in spaced, freely raisable relation to said partition to provide passages for the flow of air therebetween from said warm air openings to said central opening, and a central element of thin 20 metal extending between said side elements and supported thereon in freely raisable relation thereto; whereby to provide an ice rack in which the central element may be readily removed from its supports and the side elements thereafter removed from their supports to facilitate 25 cleaning.

HARRY L. MERRILL.
